UNITED STATES PATENT OFFICE.

MIKE SZÜR, OF ST. CATHERINES, ONTARIO, CANADA.

LIFE-RAFT.

1,169,299.

Specification of Letters Patent. Patented Jan. 25, 1916.

Application filed October 15, 1915. Serial No. 56,106.

To all whom it may concern:

Be it known that I, MIKE SZÜR, subject of the King of Hungary, residing at St. Catherines, in the Province of Ontario and 5 Dominion of Canada, have invented certain new and useful Improvements in Life-Rafts, of which the following is a specification.

This invention relates to certain new and 10 useful improvements in life rafts.

The primary object of this invention is the provision of a raft that is of light weight and adapted to be launched from the deck of a vessel for life-saving purposes, the same being arranged for securing 15 a person thereon in suitable position, for operating a steering raft.

A further object of the device is the provision of a life raft especially adapted for 20 a single occupant who may be safely secured thereon so as to manually propel the raft as well as to steer the same.

A still further object of the invention is to provide an individual life raft adapted 25 for the safe accommodation of a person in a reclining position who may readily navigate thereon, the head end of the raft being slightly elevated.

With these general objects in view and 30 others that will appear as the nature of the invention is better understood, the same consists in the novel combination and arrangement of parts hereinafter more fully described, illustrated in the accompanying 35 drawings, and pointed out in the appended claims.

In the drawings forming a part of this application and in which like-designating characters refer to corresponding parts 40 throughout the several views:—Figure 1 is a vertical longitudinal sectional view of the device. Fig. 2 is a top plan view thereof. Figs. 3 and 4 are vertical transverse sectional views taken upon lines III—III and 45 IV—IV respectively.

Referring more in detail to the drawings, the raft broadly consists of a substantially rectangular frame 10 having cylindrical floats 11 at the opposite longitudinal edges 50 thereof, the said floats having enlarged heads 12 at their adjacent ends and constituting the head end of the raft, the frame 10 at this end being slightly tapered, and the forward ends of the heads 12 being of conical formation.

A canvas covering 13 is firmly secured

upon the frame 10 and is provided with securing straps 14 for retaining a person thereon in a reclining position, loops 15 being arranged adjacent the foot end or stern 60 of the raft for the reception of the feet of the occupant. A head rest 16 is positioned at the head end or bow of the raft being arranged slightly elevated upon a drum 17.

A shaft 18 is journaled longitudinally of 65 the raft beneath the same and is provided with a stern propeller 19. A transverse operating shaft 20 is also arranged beneath the raft having a pinion 21 centrally secured thereto and in constant mesh with a 70 similar pinion 22 upon the forward end of the propeller shaft 18. The opposite outer ends of the shaft 20 are provided with operating cranks 23 and it will be evident that a person positioned upon the raft may readily operate the crank 23 by means of his 75 hands, thus actuating the propeller 19 and imparting movement to the craft.

A U-shaped rudder 24 is provided at the stern of the raft substantially encircling the 80 propeller 19 and is provided with a steering cross-piece 25 having steering cords 26 attached thereto.

From this detailed description of the device 85 it will be seen that when the raft is floating upon the water, the bow thereof will be slightly elevated by reason of the enlarged floating heads 12 and the person lying upon the canvas 13 is secured in position by means of the straps 14 and loops 15 with 90 his head mounted upon the head rest 16 and in which position the cranks 23 may readily be turned for operating the propeller 19, while the cords 26 may be utilized for steering the raft as may be desired.

While the form of the invention herein shown and described is what is believed to be the preferred embodiment thereof, it is nevertheless to be understood that minor changes may be made therein without departing from the spirit and scope of the 100 invention as claimed.

What I claim as new is:—

1. A device of the class described comprising a substantially rectangular frame 105 having a tapered head portion, cylindrical floats secured to the longitudinal edges of the said frame and having enlarged ends adjacent the said head portion, a rear propeller, oppositely arranged operating cranks 110 for the said propeller, an elevating head rest upon the said frame, a flexible covering for

the said frame, and securing straps carried by the said frame above the said covering.

2. A life raft comprising a rectangular frame, tubular side floats carried by the said frame, normally inclined when in floating position and having enlarged heads at their forward ends terminating in conical ends projecting at the bow of the raft, a canvas covering for the said frame, a head

rest carried by the said frame at the elevated end thereof, body securing straps carried by the frame and manually operated propelling and steering means carried by the frame.

In testimony whereof I affix my signature.

MIKE SZÜR.
